UNITED STATES PATENT OFFICE.

DANIEL R. BRADLEY, OF NEW YORK, N. Y.

DESIGN FOR A PERFUMERY-BOTTLE.

SPECIFICATION forming part of Design No. 16,181, dated July 28, 1885.

Application filed April 30, 1885. Term of patent 3½ years.

To all whom it may concern:

Be it known that I, DANIEL R. BRADLEY, a citizen of the United States, residing at New York, in the county and State of New York, have invented and produced a new and original Design for Perfumery-Bottles, of which the following is a specification, reference being had to the accompanying drawing, forming part thereof.

10 The purpose of my invention is to furnish a novel and effective design for perfumery-bottles; and the leading feature of my design consists of a bottle in the shape of a lady's gaiter resting on a roller-skate.

15 In the drawing, which illustrates in side elevation my newly-designed bottle, *a* represents the body of the same, which has the general form of a lady's gaiter. On the upper part of the body *a* are the scallops *b*, and similar scallops, *c*, with dots *d*, ornament the side thereof. On the front are cross-lines *e* and dots *f*, to imitate a shoe-lacing. The body *a* is closed at the top, and has a neck portion, *a'*,

and stopper *a''*. Below the gaiter-shaped body *a* is a frame or base having the general shape 25 of a roller-skate. *g* is the foot-frame, and depending therefrom are brackets *h* and axles *i*, with rollers *j*. *k* is the heel-support, around the edge of which is the ornamentation *l*. Ornamental bands *m* and *n*, extending over the 30 lower part of the body *a*, represent skate-straps. On these bands are raised ornaments *o o*, made to simulate buckles.

Having thus described my invention, what I claim as new, and desire to secure by Letters 35 Patent, is—

The design for a perfumery-bottle, consisting of the figure of a lady's boot having a closed top, and a neck with a stopper, and mounted on a base or stand having the figure 40 of a roller-skate, as shown.

DANIEL R. BRADLEY.
